1 Claim

ABSTRACT OF THE DISCLOSURE

The invention relates to an improvement for wristwatches with apparatus to show the local time for localities in the twenty-four time zones based on the universal time system. The object of the invention is to provide a useful wristwatch of novel design in a particularly small wristwatch casing, simple in construction and operation, adapted to accurately and instantly furnish the time for principal localities in the twenty-four time zones. The watch mechanisms used are of a standard design and the twenty-four hour dial is automatically rotated by the watch mechanism.

FIG. 1 is a plan view of the face of the improved wristwatch embodying the present invention.

FIG. 2 is a diagrammatic plan view of a portion of the mechanism wherein only the parts required for the understanding of the invention have been shown.

The present invention is shown in FIG. 1, wherein, the face of the wristwatch 1 containing the regular twelve hour dial 2 is smaller than the wristwatch casing 3 and is held in place by four brackets 4. The hour hand 5 completes one revolution in twelve hours, minute hand 6 completes one revolution per hour and second hand 7 completes one revolution per minute. On the outer periphery of the stationary wristwatch face 1 is a circular opening 8, and below the opening 8 is a manually rotatable disk 9 with an aperture 10 through which is visible rotary disk 11. Rotary disk 11 containing the twenty-four hour dial 12 representative of universal time completes one revolution in twenty-four hours by suitable watch mechanism and gearing in synchronization with hour hand 5 and minute hand 6. Twenty-four hour dial 12, which is viewed through opening 10, can be manually adjusted by suitable gearing by rotating knob 13. Below rotatable disk 9 and concentric to rotary disk 11 is a stationary annular rim 14 with the names imprinted upon it of geographical locations 15 for the twenty-four time zones in their positional arrangement relative to the international date line. Rim 14 is also viewed through aperture 10. Rotatable disk 9 containing aperture 10 is manually revolved by suitable gearing by rotating knob 16 to find the locality 15 for which the correct time is desired. Since the hour hand 5 and universal twenty-four hour dial 12 will have been synchronized to indicate the same time on both graduations, the universal time 12

2

and locality desired 15 will be in juxtaposition. The corresponding time 12 of any desired locality 15 can now be read through aperture 10 for all the time zones by manually rotating disk 9 by means of knob 16.

For the twenty-four hour dial, the time readings have been limited to hours only, since the minutes shown by the minute hand would be the same for international twenty-four time, as they are for local time.

An alphabetical list of the principal countries, states and cities of the world will accompany each wristwatch. The list will indicate the time zone they are in, as related to the localities shown on dial 14. Thus, it will be possible to immediately determine the time for major localities in the world.

The world time wristwatch provides a novel device, which is easily understood, for instantly reading the standard time of localities in different time zones. Changes in detail may be made to the form of invention herein shown and described, without departing from the spirit of the invention.

I claim:

1. A universal adapted wristwatch to indicate local time for the observer and for principal localities in the various time zones around the world on a twenty-four hour system, comprising a stationary dial having twelve hour graduations thereon representative of local time, below said dial a larger rotatable circular disk with an aperture, said circular disk having means whereby it may be manually rotated, below said circular disk a rotary dial concentric with said stationary dial, said rotary dial having twenty-four hour graduations thereon representative of universal time, said rotary dial having means whereby it may be manually set to show the universal time corresponding to local time on said stationary dial, below said circular disk and concentric with said stationary and rotary dials is a stationary flat annular rim having a scale thereon with names representative of different geographical locations for the various time zones, an hour hand, a minute hand, means to drive said hour and minute hands and said rotary twenty-four dial, to indicate time for a locality shown on said annular rim visible through aperture in said circular disk.
